COMPRESSOR UNLOADING MECHANISM

Hewitt A. Gehres, Mount Vernon, Ohio, assignor to Cooper-Bessemer Corporation, Mount Vernon, Ohio, a corporation of Ohio

Application January 10, 1939, Serial No. 250,093

3 Claims. (Cl. 230—21)

Compressor unloading mechanisms have been long known wherein a valve was employed to open communication between the cylinder space and a clearance chamber or otherwise relieve the pressure in the cylinder when it was desired to have the compressor operate at less than full capacity. The present invention has to do with devices of the above character and aims in one of its aspects to provide a compressor unloading mechanism so combined with the ordinary suction or discharge valve constructions as to enable unloading steps to be carried out without requiring special or awkward modification of the cylinder construction. In accordance with the invention many different unloading stages may be obtained in a simple way. Further objects and advantages of the invention will be in part obvious and in part specifically referred to in the description hereinafter contained which, taken in conjunction with the accompanying drawings, discloses the invention as applied to unloading mechanism of certain specific constructions; from the standpoint of the invention in its broader aspects however the disclosure should be considered as merely illustrative of the principles of the invention. In the drawings—

Fig. 1 is a central longitudinal section taken through an unloading mechanism constructed to operate in accordance with the invention, and shown in operative position with respect to adjacent parts of a compressor cylinder.

Fig. 2 is a bottom plan view of the mechanism shown in Fig. 1.

Fig. 3 is a central longitudinal section showing a compressor cylinder equipped with several specific forms of unloading mechanism which may be used to enable multi-step unloading to be carried out in accordance with the invention.

Figs. 4 to 8 are schematic views showing various multi-stage unloading systems operating in accordance with the invention.

In accordance with one phase of the present invention I combine with known types of compressor suction or discharge valves, or both, further valve members which form a constituent part of the valve structure but which may be operated separately from the usual suction or discharge controlling valve members, to relieve the pressure within the cylinder when it is desired to unload the compressor.

In Figs. 1 and 2 the invention is disclosed as applied to a compressor valve mechanism of the general type disclosed in U. S. Patent No. 1,890,051 issued to me on December 6, 1932, the valve mechanism as a whole being mounted in an open-

ing 1 in a compressor cylinder wall 2, which opening communicates with the cylinder space 3 at one end of the cylinder.

The illustrated construction of Fig. 1 is of a discharge valve mechanism which includes a plate-like valve seat member 4 having a series of arcuate passageways 5 extending therethrough, and a movable annular valve member 6 interposed between valve seat 4 and an annular valve guard 7, the movable valve member 6 seating against the walls which define arcuate passageways 5 when the valve is closed and moving toward the guard 7 when the valve is open, so as to permit the discharge of compressed gas from the cylinder space 3 through the valve into an annular passageway 8 through port 9 into a discharge conduit 10 in the cylinder wall. As shown, a spacer piece 11 holds the parts 4 and 7 in proper position and is in turn held in position by the valve cap 12, which latter is clamped to the cylinder wall by bolts 13 acting to compress a gasket 14 between cap 12 and spacer piece 11 and a gasket 15 between valve seat 4 and an opposed shoulder in the cylinder wall, to prevent leakage.

An unloading valve member is combined with the discharge valve structure above set forth; in the form of the invention under discussion, this unloading valve mechanism includes a movable poppet valve member 16 having a stem 17 extending longitudinally through an unloading passageway 18, the valve member 16 when closed engaging a valve seat 19 in a sleeve 20 which surrounds the unloading passageway 18 above described, and is received centrally within valve seat 4, valve guard 7 and spacer piece 11. As shown a nut 21 engages between collar 20 and spacer piece 11 to clamp the above parts together. Thus an unloading valve construction is provided within the confines of the usual compressor valve mechanism, and which requires no additional special construction of the cylinder wall 2, beyond the recess therein which is provided to receive the discharge valve mechanism proper. The unloading mechanism therefore may be easily incorporated into existing cylinder constructions.

As shown in Fig. 1, the unloading valve 16 is guided by lugs 22 on the valve seat 4 in moving between closed position and the open position shown in Fig. 1, the valve stem 17 being received within a bearing 23 held in position by a spider 24. A spring 25 acting between the spider 24 and a collar 26 on valve 17, urges the valve 16 toward closed position, and when it is desired

to unload the cylinder, valve member 16 is held open by suitable means. As shown in Fig. 1, a plunger 27 is mounted in valve cap 12 for the above purpose, the plunger 27 being pressure-controlled by a piston 28 operating in cylinder 29 having a control passageway 30 leading thereto.

In the particular form of the invention which is shown in Fig. 1, the unloading passageway 18 communicates through a passageway 31 in cap 12, with a clearance bottle 32 indicated diagrammatically in Fig. 1 as attached to cap 12, and which will be of such volume as is required to unload the compressor to the desired extent when valve 16 is open.

In Fig. 3 I have shown a compressor cylinder having two suction valve mechanisms and two discharge valve mechanisms, each equipped with unloading valve members operating in accordance with the present invention to enable multi-stage unloading of the compressor to be carried out. As shown in Fig. 3 the suction conduit 33 communicates through suction passages 34 with the suction valve mechanisms indicated generally by numerals 35 and 36 which are mounted respectively in the cylinder openings 37 and 38 at the opposite ends of the cylinder. Likewise the discharge conduit 39 is in communication through discharge passageways 40 with the discharge valve mechanisms denoted generally by numerals 41 and 42 which are respectively received within openings 43 and 44 in the opposite ends of the cylinder. The valve 41 may be taken as similar in construction and mode of operation to the one previously described in connection with Figs. 1 and 2, and is shown as controlling communication to a clearance bottle 45. The discharge valve mechanism 42 likewise controls communication to a clearance bottle 46, and is similar in construction to the valve mechanism described in connection with Fig. 1 except that the valve rod 17a (Fig. 3) is opened by means of a manually operated screw-threaded plunger 27a having a hand wheel 47 attached thereto. The suction valve mechanism 35 may also be taken as similar to the valve mechanism shown in Fig. 1, except that the valve guard 7b is interposed between the valve seat 4b and the cylinder space, and with the further modification that the valve cap 12b is provided with one passage 31b which leads to a clearance bottle 48, and a further passage 49 which leads to a valve 50 urged to move away from its seat by spring 51, and when open communicating through pipe 52 with the suction conduit 33. Thus when the unloading valve member 16b is open, a partial unloading effect will be imposed upon the corresponding end of the cylinder by the clearance bottle 48, unless or until valve 50 is unseated, in which latter event the pipe 52 bypasses gas under pressure from the cylinder space back into the suction conduit 33 to completely unload the corresponding end of the cylinder. Valve 50 may be held closed or permitted to open, by suitable means such as piston 50a operating in cylinder 50b having a control passage 50c.

The suction valve mechanism 36 is shown as somewhat modified in construction and mode of operation as compared to the one last above described, in that no clearance chamber is associated therewith, and its unloading valve when open affords communication from the corresponding cylinder space back into the suction passageway 34, thus bypassing the suction valve proper and completely unloading the corresponding end of the cylinder. As shown in

Fig. 3, the sleeve 20c has ports 53 therein which communicate through corresponding openings 54 in the spacer piece 11c, with suction passageway 34. To cooperate in affording certain partial unloading stages, a further clearance chamber 55 may be provided in the head end of the cylinder, communication to which is controlled by a valve 56 provided with suitable mechanism such as the threaded rod 57 and hand wheel 58 for adjusting the same to open or closed positions.

Valve mechanisms as above described may readily be employed to afford a variety of unloading sequences. In Fig. 4, for example, I have indicated diagrammatically a compressor cylinder equipped with suction valves 59 which may be taken to be of previously known construction, and discharge valves 60 which may be taken to be the same as the valve mechanism shown in Fig. 1, a valve 61 (and associated parts) similar to the valve 56 being provided at the head end of the cylinder. This arrangement will afford five step unloading as follows: For full load both valves 60 and valve 61 are closed; for one-quarter unloading valve 61 is open, both valves 60 remaining closed; for one-half unloading valve 60 at the right hand end of the cylinder is open, the other valve 60 and valve 61 being closed; for three-quarter unloading the valve 60 at the right hand end of the cylinder and valve 61 are open, the other valve 60 remaining closed; and for full unloading both valves 60 are open.

Fig. 5 illustrates a cylinder construction involving two suction valve mechanisms similar to valve mechanism 36 previously described, and having the unloading valves 62, and also having a valve 61 as above described in connection with Fig. 4. For full load both valves 61 and 62 are closed; for one-quarter unloading valve 61 is open, both valves 62 remaining closed; for one-half unloading valve 62 at the right hand end of the cylinder is open, and valve 61 and the other valve 62 closed; for three-quarter unloading valve 61 and the valve 62 at the right hand end of the cylinder are open, the other valve 62 being closed; and for full unloading both valves 62 are open. The discharge valves 63 of Fig. 5 may be of previously known construction.

Fig. 6 illustrates an arrangement similar to Fig. 5 except that the discharge valve mechanisms instead of the inlet valve mechanisms, are constructed to provide for the unloading. In Fig. 6 the suction valves 64 may be regarded as of previously known construction, the valve 61 is as previously described, and the discharge valve mechanisms are provided with unloading valves 65 as previously described in connection with valve mechanism 36, except that a pipe 67 is provided to afford communication between the valves 65 (constituting parts of the discharge valve mechanisms) and the suction passage of the compressor. The sequence of unloading steps in Fig. 6 is the same as described in connection with Fig. 5. In other words, valves 65 plus the pipe 67 of Fig. 6, function in the same way as the valves 62 of Fig. 5.

Fig. 7 illustrates another arrangement, the valve 61 being as previously described, and the discharge valves 68 being of any suitable or previously known type. In Fig. 7 the suction valve mechanism at the head end of the cylinder is provided with an unloading valve 69 similar to valve 62 described in Fig. 5, and the suction valve mechanism at the right hand end of the cylin-

der is provided with an unloading valve 70 similar to the one described in Fig. 3 in connection with valve mechanism 35. In other words, when valve 70 is open, the corresponding cylinder space communicates with a clearance chamber 71 to afford partial unloading; but when a valve 72 in Fig. 7 (similar to valve 50 of Fig. 3) is also open a by-pass is formed between the cylinder space and the suction passageway, thus fully unloading the corresponding end of the cylinder. In Fig. 7 the sequence of unloading steps is as follows: When fully loaded all of the valves 61, 69 and 70 are closed; for one-quarter unloading valve 61 is open, valves 69 and 70 being closed; for one-half unloading valve 61 is open and valve 70 is open to clearance chamber 71, valves 69 and 72 being closed; for three-quarter unloading valves 61, 70 and 72 are open, valve 69 being closed; for full unloading valves 69, 70 and 72 are all open.

According to Fig. 8 the suction valve mechanisms at opposite ends of the compressor are provided with unloading valves 73 and 74 similar to the valve 70 described in Fig. 7, which control communication respectively to clearance chambers 75 and 76, and also operate in conjunction respectively with valves 77 and 78, both similar to the valve 72 in function. In Fig. 8, for full load both valves 73 and 74 will be closed; for one-quarter unloading valve 73 will be open to clearance chamber 75, valve 74 and valve 77 remaining closed; for one-half unloading valves 73 and 74 will be open for communication respectively to clearance chambers 75 and 76, valves 77 and 78 remaining closed; for three-quarter unloading valves 73 and 77 will be open, also valve 74, but valve 78 will be closed; for full unloading all of the valves 73, 74, 77 and 78 will be open. In Fig. 8 the discharge valves 79 may be regarded as of any suitable or previously known construction.

The number of unloading steps which may be provided in any given installation will depend upon the number of suction and discharge valve mechanisms employed, and the extent to which they are all equipped with unloading valves of the character above described, as well as the particular way in which the unloading valves are connected. Unloading valves of the type above described in connection with valve mechanism 35 will afford two unloading steps, whereas the simpler form described in connection with the valve mechanism 41 for example provides only one unloading step. The arrangement of Fig. 3 will provide for unloading in a greater number of stages than above described.

While the invention has been disclosed as carried out by the above described specific constructions, it should be understood that many changes may be made therein without departing from the invention in its broader aspects, within the scope of the appended claims.

I claim:

1. In combination, a compressor cylinder including suction and discharge valve mechanisms having rigidly mounted valve seat members and movable valve members constructed and arranged to periodically open and close communication through said valve seat members, at least one of said valve mechanisms having therein an unloading passageway leading to the cylinder space which is additional to the parts above set forth, and an unloading valve member also additional to the parts above mentioned, said unloading valve member provided with means for holding the same in positions respectively opening and closing communication between the cylinder space and said last mentioned passageway, said last mentioned passageway communicating with the suction passage of the compressor.
2. In combination, a compressor cylinder having an unloading passageway therein, an unloading valve member provided with means for holding the same in positions respectively opening and closing communication between the cylinder space and said unloading passageway, a clearance chamber communicating with said passageway, and a further valve member controlling communication between said passageway and the suction passage of the compressor.
3. In combination, a compressor cylinder including suction and discharge valve mechanisms having rigidly mounted valve seat members and movable valve members constructed and arranged to periodically open and close communication through said valve seat members, at least one of said valve mechanisms having therein an unloading passageway leading to the cylinder space which is additional to the parts above set forth, and an unloading valve member also additional to the parts above mentioned, said unloading valve member provided with means for holding the same in positions respectively opening and closing communication between the cylinder space and said last mentioned passageway, a clearance chamber communicating with said passageway and a further valve member controlling communication between said passageway and the suction passage of the compressor.

HEWITT A. GEHRES.
